UNITED STATES PATENT OFFICE.

WILLIAM HENRY LAUTZENHEISER, OF ANSONIA, CONNECTICUT, ASSIGNOR
OF ONE-HALF TO CHAUNCEY C. BALDWIN, OF SAME PLACE.

WIRE-DRAWING APPARATUS.

SPECIFICATION forming part of Letters Patent No. 549,322, dated November 5, 1895.

Application filed July 30, 1895. Serial No. 557,573. (No model.)

To all whom it may concern:

Be it known that I, WILLIAM HENRY LAUTZENHEISER, of Ansonia, in the county of New Haven and State of Connecticut, have invented a new Improvement in Apparatus for Drawing Wire; and I do hereby declare the following, when taken in connection with the accompanying drawings and the letters of reference marked thereon, to be a full, clear, and exact description of the same, and which said drawings constitute part of this specification, and represent, in—

Figure 1, a plan view of a wire-drawing apparatus constructed in accordance with my invention; Fig. 2, a view thereof, in vertical cross-section, on the line *a b* of Fig. 1.

My invention relates to an improvement in apparatus for drawing wire, the object being to produce a simple, compact, durable, and effective device having a large capacity for work of superior character and requiring the minimum of time and labor for attention and repair.

With these ends in view my invention consists in an apparatus having certain details of construction and combinations of parts, as will be hereinafter described, and pointed out in the claims.

In carrying out my invention I employ two horizontally-arranged drums *A* and *A'*, both of which revolve in partial immersion in a lubricant *B*, located within a vat *C*. The drum *A* is mounted upon one end of a shaft *D*, having bearing in boxes *D' D'* and provided at points between the said boxes with a sprocket-wheel *D²*, and also at a point beyond the box *D'* with a fixed pulley *D³* and a loose pulley *D⁴*. The drum *A'* is mounted upon a shaft *D⁵*, mounted in boxes *D⁶ D⁶* and provided between the said boxes with a sprocket-wheel *D⁷*, over which passes a chain *D⁸*, also passing over the sprocket-wheel *D²*, whereby the drum *A'* is driven at the same speed as the drum *A*. If desired, of course the power might be applied through the shaft *D⁵*, and by gearing instead of pulleys. A series of dies *E*, arranged parallel with the drums and between them, is mounted upon a horizontal table *E'*, supported at its inner end by a bracket *E²*, secured by screws *E³* to the inner wall of the vat *C*. The said dies

are supported or backed up by an upwardly-extending flange *E⁴*, formed integral with the table *E'*, extending parallel with the length thereof, and having its upper edge constructed with a series of notches *E⁵*, arranged in alignment with the apertures *e* of the dies, which may be secured either to the body of the table or to the flange, or both.

The lubricant, of whatever character it may be, is supplied to the dies by means of the drum *A*, to which a film of lubricant will adhere as the drum revolves. This film of lubricant is scraped from the top of the drum by means of a scraper *F*, consisting of a long plate, the outer edge of which is reduced in thickness and concaved upon its under surface to conform to the curvature of the drum, and the inner edge of which is secured by screws *f* to the adjacent edge of the table *E'*, which is constructed for the purpose with a recess or rabbet *E⁶*. The said table has formed in it at a point between the scraper *F* and the flange *E⁴* a horizontal parallel trough *E⁷*, in which the lubricant scraped off from the drum *A* collects and through which it flows back into the vat again after having performed the office of lubricating the wire and the dies, which latter are, as shown, set down into the trough and bear against one of the side walls thereof.

It will be understood that the wire to be drawn is wound over both drums, passing, first, through the die having the largest aperture and the notch aligned therewith, thence to the drum *A'*, down, over, and under the same, thence under, up, and over the drum *A* to the die of the next smaller aperture and the notch aligned therewith, thence over, down, and under the drum *A'*, thence under, up, and over the drum *A*, and so on. After the wire has passed through all of the dies it is wound upon a receiving-drum, which is not shown, but which may be of any suitable construction and arrangement. Another drum or reel may also be employed for feeding the wire to be drawn to the drums.

It is apparent that in carrying out my invention some changes in the construction shown and described may be made. I would therefore have it understood that I do not limit myself to the exact form herein shown;

but hold myself at liberty to make such variations therefrom as fairly fall within the spirit and scope of my invention.

Having fully described my invention, what 5 I claim as new, and desire to secure by Letters Patent, is—

1. In an apparatus for drawing wire, the combination with a vat in which a lubricant is placed, of two horizontally arranged drums, 10 means for driving the same, a horizontal table located between the drums, a horizontally arranged series of dies mounted upon the said table, and a scraper mounted upon the table in a position adjacent to one of the 15 drums from which it scrapes the lubricant adhering thereto, and brought up from the bath in which the drum is partially immersed, substantially as described.

2. In an apparatus for drawing wire, the 20 combination with a vat in which a lubricant is placed, of two horizontally arranged drums, one of which is partially immersed in the lubricant, a horizontal table located between the drums, a series of dies secured to the said 25 table, a scraper secured to the table in position to scrape the film of lubricant from the

drum immersed therein and a trough located in the table at a point between the dies and scraper, and receiving the lubricant scraped off from the drum with which the scraper is 30 in contact, substantially as described.

3. In an apparatus for drawing wire, the combination with a vat designed to contain a lubricant, of two horizontally arranged drums, one of which is partially immersed in 35 the lubricant in the vat, a horizontally arranged table supported at its inner edge by a bracket attached to the inner wall of the vat, having a longitudinal trough formed in it, a horizontal series of dies mounted upon 40 the table, and set into the said trough, and a scraper attached to one edge of the table in position to scrape the lubricant adhering to the drum rotating in the bath thereof, substantially as described. 45

In testimony whereof I have signed this specification in the presence of two subscribing witnesses.

WILLIAM HENRY LAUTZENHEISER.
